FIG. 5 INVENTOR
W-24 GEORGE W. AMES

INVENTOR
GEORGE W. AMES
BY *Paul & Paul*
HIS ATTORNEYS

UNITED STATES PATENT OFFICE.

GEORGE W. AMES, OF BRAINERD, MINNESOTA.

ADJUSTABLE GUARD FOR WATER-GAGE GLASSES.

SPECIFICATION forming part of Letters Patent No. 769,452, dated September 6, 1904.

Application filed April 30, 1904. Serial No. 205,690. (No model.)

To all whom it may concern:

Be it known that I, GEORGE W. AMES, of Brainerd, Crow Wing county, Minnesota, have invented certain new and useful Improvements in Adjustable Guards for Water-Gage Glasses, of which the following is a specification.

My invention relates to a water-gage glass for steam-boilers; and the object of the invention is to provide a device consisting of a shield or guard to protect the engineer and fireman from injury by steam and flying glass resulting from the breaking of the water-glass.

15 A further object is to provide a guard that is adapted for use on water-glasses of different length and also upon lubricating-glasses.

The invention consists generally in providing an adjustable guard that can be readily adapted for water-gage glasses of different length.

Further, the invention consists in various constructions and combinations, all as herein-after described, and particularly pointed out 25 in the claims.

In the accompanying drawings, forming part of this specification, Figure 1 is a vertical section of a water-gage glass and guard embodying my invention. Fig. 2 is a vertical section on the line *x-x* of Fig. 1 looking toward the back of the guard. Fig. 3 is a horizontal section on the line *y-y* of Fig. 1. Fig. 4 is a similar view on the line *z-z* of Fig. 1 looking toward the under side of the guard. Fig. 5 is a section on the line *w-w* of Fig. 1. Figs. 6, 7, and 8 are details showing the means for adjusting the device to adapt it to water-glasses of different length. Fig. 9 is a sectional view through a portion of one of the heads.

40 In the drawings, 2 and 3 are the gage-cocks at the top and bottom, respectively, of the water-glass 4 and connected therewith by the usual coupling 5, having gaskets 6, that form a close joint with the wall of the tube. The guard is provided with heads 7 and 10, having dovetailed slots 11 and 11', wherein correspondingly-shaped plates 12' and 12'' are fitted. These plates are readily removable to permit

the convenient placing of the guard in its position around the water-glass, and the lower plate has dowel-pins 13', fitting within recesses 13" in the edges of the slot. I prefer to bevel the edges of the slots and provide corresponding edges on the plates, as shown 55 in Fig. 9, and when the couplings have been inserted into the heads and the lock-nuts 9 tightened, one being turned up and the other down, the guard will be held firmly in place and the water-glass drawn to its proper position between the gage-cocks. By removing the plates from the slotted heads the guard can be attached or detached from the couplings without removing the water-glass.

The head 7 is provided on three sides with 65 slots 12 to receive the glass panels 13, that inclose the water-glass on three sides, said panels being of sufficient thickness to withstand the strain resulting from the sudden breakage of the water-glass. The lower ends of 70 these panels fit within grooves 14 in the head 10 and are locked therein by means of brackets 15, that are adjustably secured to the head 7 by means of screws 16, that fit within slots 17 in said brackets. By loosening these screws 75 the brackets can be raised or lowered for the purpose of adjusting them to the length of the panels. This construction allows the guard to be adjusted to adapt it to the variation in the thickness and number of the gaskets used 80 in connection with the gage-cock couplings. Upon loosening the screws 16 the brackets or clips can be readily adjusted or removed to allow access to the panels. The corners of the ends or heads 7 and 10 on the front side 85 are provided with annular recesses 18 to receive angle-bars or corner-plates 19, that lap over the abutting corners of the glass panels and hold them in place and at the same time present a neat finished appearance to the front 90 of the guard. Clips 20 are provided on the under side of the head 10 to support the corner-plates.

On the back side of the device the heads are connected by a metallic plate 21, having a series of holes 22, produced by pressing or punching out tongues 23 from said plate. These tongues are arranged at an incline, as

shown, and serve to direct the water and steam and broken glass down upon the engine-deck.

The device shown in Figs. 1 and 2 can be adapted to fit water-glasses of different length by setting up the device, marking the panels and plates, then removing them, and cutting them off to the desired length.

In Figs. 6 and 7 I have shown a modification in the construction of the corner bars or plates which consists in providing a plate 24, fitting in the head of the guard in the usual manner and telescoping with a corner-plate 25, that is mounted in the lower head and provided with a longitudinal slot 26, wherein a thumb-screw 27, carried by the plate 24, is slidable. By loosening this screw and adjusting the corner-plates the heads of the guard can be moved toward or from each other to adapt the device for water-glasses of different length. The heads and corner-plates of the guard can be stamped out of sheet metal suitably finished, and the panels are preferably made out of heavy plate-glass, except the one at the rear, which is of metal.

This device is adapted for use on steam-boilers of all types, but is particularly designed for locomotive-boilers, where the position of the engineer and fireman in the cab exposes them to personal injury in case of breakage of the glass. The device is also adapted for use with lubricating-glasses after being cut a suitable length for the purpose.

The slots 12 are beveled on one side to permit the glass panels to be conveniently inserted from beneath in case the gage-cock should be in the way above the head-plate. The device is adapted for use on any length of water-gage glass by assembling the parts and marking and cutting off the panels and back and corner plates to the desired length. If the construction shown in the modification is employed, it will only be necessary to cut off and mark the panels, the angle or corner plates telescoping to correspond to the length of the water-glass.

I claim as my invention—

1. The combination, with the water-gage cocks and their couplings, of a water-gage supported between said couplings, heads or end plates mounted on said couplings and closing the top and bottom of the guard against the passage of glass and water, glass panels connecting said heads, and a metallic panel connecting said heads at the rear of said guard and having a series of perforations arranged to direct the water and broken glass down upon the engine-deck.

2. In a guard for water-gage glasses, the combination, with a head or end plate, of panels removably mounted therein, and brackets mounted on said head and adjustable toward or from the end of said panels, for the purpose specified.

3. A guard for water-gage glasses, comprising

heads or ends, glass panels connecting said heads, a metallic panel connecting said heads and having a series of depending tongues formed by pressing or punching out slots or holes therein, for the purpose specified.

70

4. A guard for water-gage glasses comprising heads or ends adjustable toward or from each other and closing the top and bottom of the guard against the passage of water and glass, a panel connecting said heads and adjustable in one of them to allow said heads to be moved toward or from each other to adapt the guard for use on water-glasses of different length.

75

5. A guard for water-glasses, comprising head or end plates, panels connecting the said plates, telescoping angle-plates connecting said head-plates at the intersection of said panels, said telescoping plates having a slot-and-thumb-screw connection, for the purpose specified.

80

6. A guard for water-glasses, comprising two heads, and panels connecting the same, corner or angle plates provided at the intersection of said panels, each corner-plate comprising two sections attached respectively to said heads and having a sliding connection with each other.

90

7. The combination, with the water-gage cocks and their couplings, of a water-glass connecting said couplings, end plates fitting on said couplings and held between the lock-nuts thereof and said cocks, one plate being above and the other below its locking-nut and closing the top and bottom of the guard against the passage of water and glass, and panels connecting said heads.

95

8. A guard for a water-gage glass, comprising heads having slots to receive the gage-couplings, a plate removably fitting said slots, and a series of glass panels connecting said heads.

100

9. A guard for a water-gage glass comprising two heads secured to the gage-cocks and having dovetailed slots, correspondingly-shaped plates removably fitting in said slots, and panels connecting said heads.

110

10. The combination, with the water-gage cocks and their couplings, of a water-glass connecting said couplings, end plates fitting on said couplings and held between the lock-nuts thereof and said cocks, one plate being above and the other below its locking-nut and closing the top and bottom of the guard against the passage of water and glass, corner-plates connecting said heads and being adjustable to permit the use of said guard on glasses of different length, and glass panels connecting said heads between said corner-plates.

115

In witness whereof I have hereunto set my hand this 16th day of April, 1904.

GEORGE W. AMES.

In presence of—

MILTON MCFADDEN,
R. J. HARTLEY.
